(57) **CLAIM**

The ornamental design for an accessory for vacuum cleaner as shown and described.

DESCRIPTION

FIG. 1 is a front, right and top perspective view of an accessory for vacuum cleaner, showing my design.

FIG. 2 is a front, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is an enlarged view of detail 10 in FIG. 5.

The broken lines depict portions of the accessory for vacuum cleaner that form no part of the claimed design.

The dot-dash broken lines in FIGS. 1, 5, 9 and 10 depict the boundaries of the enlargements that form no part of the claimed design.

1 Claim, 10 Drawing Sheets
